UNITED STATES PATENT OFFICE

1,992,193

WATER CIRCULATOR FOR BOILERS

Clifford M. Crane, St. Paul, Minn.

Application November 16, 1931, Serial No. 575,444

20 Claims. (Cl. 122—409)

My invention relates to improvements in boilers or like devices.

My invention relates more particularly to boiler construction wherein water is heated for the purpose of producing steam and relates to boilers of the stationary type as well as boilers for locomotives, steamboats and other steam consuming vehicles.

The principal object of my invention is to provide an improved boiler construction whereby the efficiency thereof will be greatly increased and the elimination of scale therein effected.

A further object is to provide improved circulator means for a boiler whereby increased efficiency and lower fuel consumption are accomplished.

A further object is to provide an improved boiler structure of the character described that is easily and cheaply manufactured, yet durable under strenuous working conditions and not easily capable of becoming out of order.

A further object is to provide a simple and efficient means for causing a circulation of the water at the front and lower portions of the boiler, resulting in an equal and efficient heating of the water.

Other objects and advantages will be more apparent from the following description wherein reference is had to the accompanying sheet of drawings on which

Fig. 1 is a diagrammatic view in perspective illustrating an installation of my improved water circulator as applied to a horizontal or stationary type boiler;

Fig. 2 is a section through the boiler proper on the lines 2—2 of Fig. 1;

Fig. 3 is a similar section on the lines 3—3 of Fig. 1.

In the drawing, in Fig. 1, I have shown a type of boiler 10 which may be of the usual horizontal type having a grate 12 and a firebox 14 located adjacent the front end of the boiler. The boiler is of the customary type provided with flues 16 through which the heated gases are adapted to pass from the firebox to the stack or chimney of the furnace.

The boiler may have the usual rear tube sheet 18 and a closure member 20 composed of firebrick or other suitable material which will direct the heat which passes through the flues 16 downwardly so that the same may return through the lower flues 16. The closure member 20 forms one portion of the firebrick or other suitable walls 22 which completely enclose the boiler from a position above the flues downwardly and form a com-

bustion chamber 24 around the lower portion of the boiler.

The circulating device which I choose to employ with this type of boiler may comprise a pair of main feeders 26 and 28 which are situated within the boiler adjacent the lower portion thereof and which extend back to the rear tube sheet 18 where they are attached to two arched tubings 30 and 32 which protrude through the tube sheet and extend through the combustion chamber 24 upwardly to the top of the same tube sheet where they enter and are suitably connected to the boiler at 34 and 36. Each of the main feeders 26 and 28 may be provided with a plurality of laterally extending branches 38 which may extend upwardly or sidewardly, as desired, to be capable of drawing water from various portions of the boiler proper. A plurality of openings 40 are also provided in the main feeders 26 and 28 so that water may enter these pipes at a number of different elevations as well as locations between the front and the rear of the boiler.

The arched tubings 30 and 32, as clearly shown in the drawing, extend for a considerable distance in the combustion chamber 24 and are directed in such a manner that they pass through the spaces in the combustion chamber where the most intense heat is available.

In describing the operation of a boiler of this type in conjunction with the circulator illustrated, the heat units from the firebox are forced to travel towards the combustion chamber 24 through a portion of the flues 16 and are then drawn forward through other flues 16 into the smoke box and then expelled through the stack. The smoke box and stack have not been shown but it is believed that to those skilled in the art, the reference thereto will be sufficient.

The heat in this type of furnace impinges against the lower half of the boiler shell and also the flues, the rear tube sheet and the arched tubings 30 and 32. As the heat that is produced by the combustion in the firebox 14 is drawn to the combustion chamber 24, it is transformed into gases and fumes and is then drawn through the flues into the stack. As the gases are travelling through the flues, they are radiating heat through the flues that are surrounded by water in the boiler, thereby transmitting heat to this water. By virtue of this travel, the units of heat become less as the distance of travel consumes the units of heat. For this reason we have various water temperatures in the boiler. This difference in water temperature in the boiler is due primarily to two causes: exhaustion of heat units as the

heat advances, and lack of circulation in water. The circulator which is calculated to remedy this condition, and which is composed of the two main feeders 26 and 28, is adapted to draw cold water 5 from the bottom of the boiler and expel the same through the arched tubings 30 and 32 into the upper portion of the boiler. The feeders and the arched tubes are at all times below the water 10 level of the boiler; hence they are never subjected to combustion chamber heat without being full of travelling water.

The heat in the combustion chamber, striking 15 against the tubes of the circulator, causes the water to rise or produces an agitation that creates a vacuum which replaces each particle of water generated into steam or produced into circulation. As the cooler water seeks its level at the bottom of the boiler, a circulation is produced 20 which tends to render the entire body of water within the boiler of the same temperature.

From the description thus provided, it is apparent 25 that I have provided an improved means for circulating the water of unequal temperatures in a boiler and further that I have used the heat units which would otherwise be drawn through the furnace and out through the stack. For this reason it is believed to be apparent that a much more efficient boiler construction has been provided and one wherein water will be more 30 easily and quickly heated than heretofore.

While I have illustrated and described a specific 35 embodiment and a modification thereof, I do not wish to be limited to any of the particulars shown; rather what I desire to secure and protect by Letters Patent of the United States is:

1. Apparatus of the class specified comprising 40 conduits extending through the lower part of a boiler and from a point adjacent the lower end of said boiler through a combustion chamber of a furnace to a point adjacent the upper end of the boiler, said conduits having perforated branch conduits disposed at points along the length of the boiler.

2. Apparatus of the class specified comprising 45 conduits extending through a boiler and leading from one point of the boiler to another and through a combustion chamber of a furnace, said conduits having perforated branch conduits disposed at points along the length of the boiler.

3. Apparatus of the class specified comprising 50 conduits extending through the lower part of a boiler and from said boiler through a combustion chamber of a furnace to a point adjacent the upper end of the boiler, said conduits having a plurality of inlets therein and perforated branch conduits extending therefrom and opening in the water space of the boiler.

4. Apparatus of the class specified comprising 55 main conduits extending through the lower part of a boiler and from the lower end of said boiler through a combustion chamber of a furnace to a point adjacent the upper end of the boiler, branch conduits extending from the main conduits said main and branch conduits having 60 means formed therein to provide a plurality of inlets at different levels therein.

5. A circulator for a boiler comprising means 65 for conveying water from the lower part of the upper part of the boiler, said means extending through the lower part of said boiler and arranged to pass through a heating medium adjacent the boiler, and a perforated branch conduit for feeding water from remote points to the water conveying means.

75. 6. A circulator for a boiler comprising means for

conveying water from the lower part to the upper part of the boiler, said means extending through the lower part of said boiler and arranged to pass through a heating medium adjacent the boiler and said means having a plurality of perforations and perforated branch conduits to provide inlets at different levels in said boiler.

7. A circulator for a boiler comprising means for conveying water from the lower part to the upper part of the boiler, said means extending through the lower part of said boiler and arranged to pass through a heating medium adjacent the boiler, and said means having a plurality of perforations and perforated branch conduits to provide inlets at different levels and at 15 different locations in said boiler.

8. Apparatus of the class specified comprising circulatory pipes in the boiler combustion chamber for conveying water from the lower part to the upper part of the boiler, said circulatory pipes extending through a portion of the lower part of said boiler and having projecting branch inlets at a plurality of separated points.

9. Apparatus of the class specified comprising circulatory pipes in the boiler combustion chamber for conveying water from the lower part to the upper part of the boiler, said circulatory pipes extending through a portion of the lower part of said boiler and having branch conduits arranged to provide inlets at a plurality of 25 separated points and different levels.

10. The combination with a horizontal boiler, a firebox at one end thereof and a combustion chamber of a feeder pipe extending along the inside bottom wall of said boiler passing through a 35 vertical wall thereof, then upwardly through said combustion chamber and re-entering said boiler at a point below the water level therein, said feeder pipe having a plurality of branches reaching different elevations and a plurality of ports at 40 different points.

11. Apparatus of the class specified comprising a boiler, main feeder conduits extending along the bottom of the boiler, lateral branches diverging to points remote from the main feeder and having 45 openings therein, circulating conduits leading from the main feeder conduits to the top of the boiler, and means for causing circulation through the conduits.

12. Apparatus of the class specified comprising 50 a boiler, main feeder conduits extending along the bottom of the boiler, a series of lateral branches diverging to points remote from the main feeder and having openings therein, circulating conduits leading from the main feeder conduits to the top 55 of the boiler, and means for causing circulation through the conduits.

13. Apparatus of the class specified comprising a boiler, main feeder conduits extending along the bottom of the boiler, lateral branches diverging from the main feeder and having openings 60 therein, circulating conduits leading from the main feeder conduits to the top of the boiler, and means for causing circulation through the conduits.

14. Apparatus of the class specified comprising a boiler, main feeder conduits extending along the bottom of the boiler, a series of lateral branches diverging from the main feeder and having 65 openings therein, circulating conduits leading from the main feeder conduits to the top of the boiler, and means for causing circulation through the conduits.

15. Apparatus of the class described comprising a boiler, main feeder conduits extending 75

5 through and from a point within the lower end of the boiler to a point adjacent the upper end of the boiler, a branch conduit extending from the main feeder conduits having a perforation therein remote from the main feeder conduits, and means for causing circulation through the conduits.

10 16. Apparatus of the class described comprising a boiler, main feeder conduits extending through and from a point within the lower end of the boiler to a point adjacent the upper end of the boiler and provided with perforations, a branch conduit extending from the main feeder conduits having a perforation therein remote from the main feeder conduits, and means for causing circulation through the conduits.

15 17. A device adapted for use in boilers comprising a conduit leading from one point of the boiler to another through a combustion chamber of a furnace and having branch conduits arranged to provide inlets at a plurality of separated points within the water space of the boiler.

18. A device adapted for use in boilers comprising a conduit leading from one point of the boiler to another through a combustion chamber of a furnace and having branch conduits arranged to provide inlets at a plurality of separated points and different levels within the water space of the boiler.

5

19. A device adapted for use in boilers comprising a conduit leading from one point of the boiler to another through a combustion chamber of a furnace and having an inlet formed therein and a branch conduit also having an inlet therein within the water space of the boiler.

10

20 20. Apparatus of the class specified comprising conduits extending through the lower part of a boiler and from a point adjacent the lower end of said boiler through a heated chamber of a furnace to a point adjacent the upper end of the boiler, said conduits having perforated branch conduits disposed at points along the length of the boiler.
